CLAIM

The ornamental design for a compressor inlet for turbocharger, as shown and described.

DESCRIPTION

FIG. 1 is a perspective view of a compressor inlet for turbocharger showing our new design;

FIG. 2 is a front view thereof;

FIG. 3 is a top view thereof;

FIG. 4 is a right view thereof;

FIG. 5 is a left view thereof;

FIG. 6 is a back view thereof;

FIG. 7 is a bottom view thereof; and,

FIG. 8 is cross-sectional view thereof taken along line 8-8 in FIG. 2.

The broken line showings of FIGS. 1-8 are environmental only and not part of the claimed design.

1 Claim, 7 Drawing Sheets
